Primary Examiner — Philip S Hyder*(74) Attorney, Agent, or Firm* — Meunier Carlin & Cursman LLC(57) **CLAIM**

The ornamental design for a drill bit, as shown and described.

DESCRIPTION

FIG. 1 is a perspective view of the drill bit, showing my new design;

FIG. 2 is another perspective view thereof;

FIG. 3 is a left-side view thereof;

FIG. 4 is a right-side view thereof;

FIG. 5 is a front view thereof;

FIG. 6 is a rear view thereof;

FIG. 7 is a top plan view thereof; and,

FIG. 8 is a bottom plan view thereof.

The broken lines shown in the drawings represent disclaimed portions of the drill bit that form no part of the claimed design.

1 Claim, 8 Drawing Sheets(56)
